FRANK C. SCHOENBUCKER AND ARTHUR H. C. TEWS, OF MILWAUKEE, WISCONSIN.

FLOAT.

Application filed October 29, 1921. Serial No. 511,469.

To all whom it may concern:

Be it known that FRANK C. SCHOENBUCKER and ARTHUR H. C. TEWS, citizens of the United States, residing at Milwaukee, county of Milwaukee, and State of Wisconsin, have invented new and useful Improvements in Floats, of which the following is a specification.

This invention relates to floats and is particularly directed to a float adapted for use of plasterers.

The usual practice in plastering is to finish the final coat while it is still damp, by rubbing it with a piece of carpet tacked upon a wooden block and continuously re-wetting the plaster immediately preceding this rubbing action or process. In this manner the various defects, such as hollows, protuberances, and irregularities generally are removed, and a finished smooth surface is produced. It frequently happens that the carpet strip will wear out before the stretch or extent of the wall has been covered. It is then necessary to withdraw the tacks or nails, remove the worn carpet, and replace it by a new piece. This requires considerable time, and if the plaster is of a quick hardening variety, it may be that considerable difficulty is experienced in subsequently finishing the remaining portion after a new piece of carpet has been positioned correctly upon the float. Also, inasmuch as the float is wet during the entire working period, and is allowed to dry over night or between successive jobs, it frequently happens that the wooden block will warp and that the hollows will have to be filled out by sticking paste board strips between the carpet and the warped portion of the block. It is also extremely difficult to properly stretch the carpet over the float and tack it in place while it is held in a stretched condition, and it will be noted that this operation necessitates the use of nails and a hammer or similar tool which may not at all times be accessible.

It is therefore a primary object of this invention to provide a float which will not have these inherent defects, but which may be readily and quickly manipulated to permit the changing of worn strips of carpet without the use of nails or hammer, which will not warp, and which will at one operation stretch and secure the carpet in position.

Further objects are to provide a float

which has a non-absorbent, non-warping body, which is of substantially the same weight as the usual floats, which will not rust, which does not require the use of nails or a hammer or any additional tools for properly positioning the new carpet strip, and which will hold the carpet in such a position that it is less likely to fray than in the usual construction of floats.

An embodiment of the invention is shown in the accompanying drawing, in which:

Figure 1 is a perspective view of the complete float.

Figure 2 is a side elevation, partly in section, with the fabric member removed.

Figure 3 is a plan view, with parts broken away, of the structure shown in Figure 2.

The float comprises a base portion 1 of metal, preferably aluminum, provided with a smooth flat bottom surface. The upper portion of this member is provided with upturned ridges of projecting ribs 2 and 3 adjacent its ends and extending completely across the member 1. A pair of lugs, as indicated at 4 and 5, are formed integrally with the member 1 adjacent its side edges, and are spaced inwardly from the end of such member.

A pair of clips 6 and 7 are hingedly mounted upon the member 1 by means of rivets or bolts 8 and 9 passed thru the lugs 4 and 5 and the inwardly directed arms 10 and 11 of the clips, respectively. These clips are each provided with an outwardly extending member, indicated respectively at 12 and 13, which is located in close proximity to and slightly spaced inwardly from the ribs or upwardly extending projections 2 and 3, as clearly shown in Figure 2. Bolts 14 and 15 are hingedly joined to lugs 16 and 17 formed integrally with the member 1 adjacent its respective ends and are adapted to extend upwardly from such member and to pass through slots 18 and 19 formed in the members 6 and 7. A pair of thumb nuts 20 and 21 are threaded upon the bolts 14 and 15 and serve to press the clips 6 and 7 downwardly.

A manipulating handle 22, which is of relatively large size, so as to form a convenient grip for the operator, is secured upon the upper side of the member 1 by means of screws 23 countersunk in the member 1 (see Figure 2). It is to be noted that the handle is tapered downwardly and outwardly and has a relatively large bearing

surface in contact with the upper surface of the member 1. In order to accommodate the size and type of handle the clips 6 and 7 are formed as indicated in the drawing, that is to say, with rearwardly extending arms 10 and 11 positioned upon opposite sides of the handle.

When it is desired to use the float, a piece of fabric 24, such for example as carpet, is positioned beneath the member 1 with its ends 25 and 26 passed over the projections or ridges 2 and 3 and beneath the portions 12 and 13 of the clips. The thumb nuts 20 and 21 are tightened so as to force the clips downwardly. It is to be noted that the bottom edges of the members 12 and 13 engage the fabric slightly inwardly of the projections 2 and 3, and thereby draw these ends downwardly over such projections, which in turn, secures the proper tensioning of the fabric across the end face of the member 1. If desired, the fabric may be slightly wider than the member 1 so as to provide a more gradually rounded edge 25 at the lateral margins of the float, as the fabric will bend upwardly about such edges.

It will thus be seen that a float has been provided which is admirably adapted for rapid and continuous use by providing for the quick renewal of the worn fabric or carpet member, and by providing means for

insuring its proper tensioning across the end face of the device. It will also be seen that a float has been provided which may be readily worked into the corners of a room, which is of substantially the same weight as the usual wooden floats, and in which auxiliary tools are not required to effect the replacement of a worn fabric or carpet strip.

If desired, the metal portions may be made from flat stock with the lugs, ears, and ridges struck up from the body portion.

We claim—

A float comprising a flat body portion of metal, a handle secured upon the upper side of said body portion, a pair of upwardly projecting ribs formed upon the upper side of said body portion and located adjacent its outer ends, a pair of pivotally mounted clips adapted to swing past said projecting ribs and to slightly clear such ribs, means for forcing said clips downwardly and retaining them in position, and a fabric strip positioned across the under side of said body portion, and having its ends extending over said ribs and engaged by said clips, whereby when said clips are forced downwardly said fabric will be drawn over said ribs, and thereby properly tensioned and secured in position.

FRANK C. SCHOENBUCKEY.
